UNITED STATES PATENT OFFICE

JOSEPH H. EASTMAN, OF OAKLAND, AND FRANCIS A. TODHUNTER, OF PALO ALTO, CALIFORNIA, ASSIGNORS TO STANDARD STATIONS, INC., OF SAN FRANCISCO, CALIFORNIA, A CORPORATION OF DELAWARE

DESIGN FOR A DISPLAY FIGURE

Application filed September 3, 1931. Serial No. 41,018. Term of patent 14 years.

To all whom it may concern:

Be it known that we, JOSEPH H. EASTMAN and FRANCIS A. TODHUNTER, citizens of the United States, residing in the city of Oakland, county of Alameda, and in the city of Palo Alto, county of Santa Clara, respectively, State of California, have invented a new, original, and ornamental Design for a Display Figure, of which the following is a specification, reference being had to the ac-

companying drawings, forming part thereof.

In the drawings Figure 1 is a plan view and Figure 2 is a side edge view of the display figure, showing our new design; disclosing the display figure as of substantial thickness.

We claim:

The ornamental design for a display figure, as shown and described.

JOSEPH H. EASTMAN.
FRANCIS A. TODHUNTER.
